UNITED STATES PATENT OFFICE

156,760

FREEZER CABINET

George Orley, Detroit, Mich.

Application January 29, 1949, Serial No. 567

Term of patent 3½ years

(CL. D67—3)

To all whom it may concern:

Be it known that I, George Orley, a citizen of the United States, residing in Detroit, in the county of Wayne, in the State of Michigan, have invented a new, original, and ornamental Design for Freezer Cabinets, of which the following is a specification, reference being had to the accompanying drawings, forming part thereof.

This is a continuation-in-part of applicant's co-pending design application, Serial No. D. 140,197, filed July 10, 1947, now abandoned.

Fig. 1 is a front elevational view of a freezer cabinet embodying my new design;

Fig. 2 is a side elevation thereof;

Fig. 3 is a top plan view thereof;

Fig. 4 is a vertical sectional view taken on line 4—4 of Fig. 1; and

Fig. 5 is a cross-sectional view taken on line 5—5 of Fig. 1.

I claim:

The ornamental design for a freezer cabinet, as shown and described.

GEORGE ORLEY.
